DESIGN FOR AN ASH TRAY

Frank Powell, Miami, Fla.

Application October 11, 1944, Serial No. 115,720

Term of patent 7 years

(Cl. D85—2)

To all whom it may concern:

Be it known that I, Frank Powell, a citizen of the United States of America, residing in Miami, county of Dade, and State of Florida, have invented a new, original, and ornamental Design for an Ash Tray, of which the following is a specification, reference being had to the accompanying drawing, forming part thereof.

Fig. 1 is a side perspective view of an ash tray showing my new design.

Fig. 2 is a rear perspective view thereof. The opposite side of the ash tray is substantially the same as shown in Fig. 1.

I claim:

The ornamental design for an ash tray, substantially as shown and described.

FRANK POWELL.
